UNITED STATES PATENT OFFICE.

RAYMOND HASKELL, OF SUMMIT, NEW JERSEY, ASSIGNOR TO THE TEXAS COMPANY,
OF NEW YORK, N. Y., A CORPORATION OF TEXAS.

DESIGN FOR AN OIL CAN.

60,342.

Specification for Design.

Patented Feb. 7, 1922.

Application filed May 6, 1921. Serial No. 467,289. Term of patent 14 years.

To all whom it may concern:

Be it known that I, RAYMOND HASKELL, a citizen of the United States, and a resident of Summit, county of Union, and State of New Jersey, have invented a new, original, and ornamental Design for Oil Cans, of which the following is a specification, reference being had to the accompanying drawing, forming a part thereof.

Referring to the drawing,

Figure 1 is a view in elevation.

Figure 2 is a plan view.

Figure 3 is a bottom plan view.

What I claim is:

The ornamental design for an oil can, as shown.

RAYMOND HASKELL.
